Attorney

UNITED STATES PATENT OFFICE.

ALPHA H. METCALF, OF ATTLEBORO, MASSACHUSETTS, ASSIGNOR TO H. A. ALLEN & CO., OF ATTLEBORO, MASSACHUSETTS.

BELT BUCKLE.

Application filed January 24, 1922. Serial No. 531,385.

To all whom it may concern:

Be it known that I, ALPHA H. METCALF, a citizen of the United States, residing at Attleboro, in the county of Bristol and State 5 of Massachusetts, have invented certain new and useful Improvements in Belt Buckles, of which the following is a specification.

This invention relates to buckles for belts and similar articles, and has for its object 10 to provide such a buckle with a body portion comprising a front plate with side flanges and against the inner face of this front plate is adjustably secured one end of the belt, its opposite end being secured to a spring 15 frame member adapted to releasably engage the side flanges whereby this end of the belt may be quickly released from the buckle body without changing the adjusted length of the belt.

With these and other objects in view, the 20 invention consists of certain novel features of construction, as will be more fully described, and particularly pointed out in the appended claim.

In the accompanying drawings:

Figure 1 is a view of the rear of the buckle, showing one end as being bound in the body 30 of the buckle while the other end is attached to the bar or bail of a releasable frame member.

Figure 2 is a central sectional edge view of my buckle, showing the belt ends as secured thereto.

Figure 3 is a perspective view showing 35 the body of the buckle with the belt retaining members removed.

Figure 4 is a perspective view of the resilient detachable frame member to which one end of the belt is permanently secured.

Figure 5 is a view of the under side of a buckle having rounding side edges and showing portions of the inturned edges of the side flanges as turned downwardly to 40 serve as guides for the U-shaped frame member.

It is found in practice to be of advantage to provide a buckle having a clamp for adjustably securing one end of the belt in the buckle and to also provide a readily detachable member for releasably securing the 45 opposite end of a belt to the buckle whereby the belt may be released from the buckle without loosing the adjustment of the belt, and the following is a detailed description

of one means by which this result may be 55 accomplished:—

With reference to the drawings 10 designates the body of a buckle which comprises essentially a front plate 11 having inturned edge flanges 12.

The edges 13 of these flanges are preferably turned inwardly to provide a guide for the belt and these flanges are provided near one end with openings or notches 14 to be engaged by the frame presently described. 60

At the opposite end of this buckle portions of the flanges are turned inwardly forming pivot ears 15 in which opposite ends of a clamp 16 are pivoted for gripping the belt portion 17 against the inner face of the front 70 plate to hold the belt firmly in any adjusted position.

In order to releasably secure the opposite end of the belt to the buckle body I have provided a substantially U-shaped frame 75 member 18 with its outer ends turned in toward each other. The side arms 19 of this frame are provided with lateral projections 20 adapted to engage the notches 14 in the body flanges and the outer end of this frame 80 is spread slightly forming stop shoulders 21 to limit the inward movement of the frame by engaging the edges of the flanges and this outer end is shaped to perform the function of a bail with a portion of its in-turned ends of the bar removed as at 22 to permit the side arms to yield laterally for the purpose of withdrawing the projections 20 from the notches 14 and upon this belt-bar of the frame I have mounted a tubular 90 ferrule or sleeve 23 for presenting a smooth surface about which the end 24 of the belt may be secured.

This sleeve is loosely mounted on the bail bar to permit the free ends of the bar to 95 readily slide thereinto to permit the compression of the side arms of the frame.

The inner portions of these projections are tapered slightly as at 25 so as to cause the side arms to compress automatically 100 and cause the projections to snap into the openings 14 when the frame is forced into position between the body flanges.

It will be noted that the recesses 14 are formed in the side flanges near their outer 105 edges, by which construction the frame is positioned in the body of the buckle by causing its inner end 26, to slide along that

portion 27 of the belt previously inserted, to be guided into position between the flange members beneath their inturned edges 13 until the projections 20 snap into the openings in the flanges whereby this end of the belt is firmly but releasably secured to the body of the buckle and may only be released by exerting a closing pressure upon the roughened laterally-projecting portions 28 of the side arms.

My improved buckle is extremely simple and practical in construction and by its use one end of the belt is retained in any desired adjusted position while the opposite end may 15 be disconnected from the buckle at will without disturbing the belt adjustment, it being only necessary to press together the exposed or bail ends of the snap fastener frame to release the same from the buckle body and 20 to push the frame back into the buckle body to cause it to automatically and securely engage the body of the buckle.

In some cases the buckle body is formed with curved sides as illustrated in Figure 25 in which case I cut the inturned flanges 13 and turn the cut portion inwardly to

serve as side guides 15 for the U-shaped bail frame 18, to facilitate the guiding of the same into operative position in the buckle body.

The foregoing description is directed solely towards the construction illustrated, but I desire it to be understood that I reserve the privilege of resorting to all the mechanical changes to which the device is 30 susceptible, the invention being defined and limited only by the terms of the appended claim.

I claim:

A belt buckle comprising a front plate 40 with side flanges having inturned guide edges, a substantially U-shaped spring frame bail member having lateral projections adapted to engage openings in said side flanges with spring pressure, a portion of 45 said guide edges being folded inwardly to guide said frame to its engaging position, and means in the buckle for holding the adjustable end of the belt.

In testimony whereof I affix my signature. 50

ALPHA H. METCALF.
